US00D992733S

(12) **United States Design Patent** (10) **Patent No.:** **US D992,733 S**
Parker et al. (45) **Date of Patent:** **** Jul. 18, 2023**

(54) **CIRCUMCISION ASSISTANCE DEVICE**

(71) Applicant: **INNOVATIVE MEDICAL TECHNOLOGY (PTY) LTD**, Cape Town (ZA)

(72) Inventors: **Cyril Norman Parker**, Cape Town (ZA); **Elisabeth Regina Parker**, Cape Town (ZA); **Jared Mark Vorster**, Cape Town (ZA); **David Christopher Wiseman**, Cape Town (ZA)

(73) Assignee: **INNOVATIVE MEDICAL TECHNOLOGY (PTY) LTD**, Cape Town (ZA)

(**) Term: **15 Years**

(21) Appl. No.: **29/702,883**

(22) Filed: **Aug. 22, 2019**

(51) LOC (14) Cl. **24-02**

(52) U.S. Cl. **D24/147**
USPC ..

(57) **CLAIM**

The ornamental design for a CIRCUMCISION ASSISTANCE DEVICE, as shown and described.

DESCRIPTION

FIG. 1 is a top perspective view of a CIRCUMCISION ASSISTANCE DEVICE showing our new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and

FIG. 8 is a bottom plan view thereof.

1 Claim, 8 Drawing Sheets
